ASH TRAY FOR VEHICLES AND THE LIKE

Harold D. Penney, Pelham, and Charles E. Whiteman, Richmond Hill, N. Y.; Elizabeth Penney, executrix of Harold D. Penney, deceased, assignors to Paul H. Bosse, Chicago, Ill.

Application May 7, 1940, Serial No. 333,708

3 Claims. (Cl. 206—19.5)

This invention relates to receivers for cigar and cigarette ash and butts and like material, and more particularly to devices of this kind suitable for ash receivers for use in closed or open automobiles though it is noted that in some of the claims the invention is not limited to use with vehicles.

Heretofore, considerable difficulty has been experienced in disposing of cigarette ashes and the like, while riding in closed automobiles, as drafts caused by the moving vehicle are likely to scatter the ashes to a very disagreeable extent.

One object of the invention is to provide a device of this kind in which the ashes and the like may be deposited without being scattered by drafts.

Another object of the invention is to provide means for conveying the ashes to the exterior while moving on the road without danger of fire.

Another object of the invention is to provide a device of this kind which will hold burning cigarette butts and the like therein until they burn up or go out, thus to prevent danger of fire in garages.

Other objects of the invention are to improve generally the simplicity and efficiency of such devices and to provide a neat artistic device or apparatus of this kind which is safe, durable and reliable in operation, economical to manufacture, and easy to install.

Still other objects of the invention will appear as the description proceeds; and while herein details of the invention are described in the specification and some of the claims, the invention is not limited to these, since many and various changes may be made without departing from the scope of the invention as claimed in the broader claims.

The inventive features for the accomplishment of these and other objects are shown herein in connection with an improved ash receiver which, briefly stated, includes a housing adapted to be mounted in the automobile and having a receiving front opening, and a bottom opening adapted to discharge ashes and the like into an upright chute extending downwardly to the exterior of the automobile. A normally yieldable raised segmental outer closure drum normally closing said front opening and provided with end walls centrally pivotally mounted on pivot pins in the end walls of the housing; while a normally raised inner drum is coaxially received in the outer drum and also pivoted on said pivot pins. A spring-pressed control member operatively connected to both of said drums yieldably raises the drums, and constrains the drums to move

together whereby the drum segments may be lowered to open said receiving opening and form a depression for receiving the ashes, the drum segments then being raised to separate and drop the ashes upon a normally horizontal platform hinged in the chute.

A link connects said platform and outer drum, whereby when the drums are raised the platform is also raised to horizontal position to receive the ashes or unburned material, and when the drums are lowered the platform is lowered to drop the material into an upwardly open elongated passage chamber communicating with the lower end of the chute and provided with a dished floor to receive the material, and front and rear open ends, whereby when the vehicle moves a draft is created for sweeping out material that may be therein.

We illustrate also a modified form which shows a drawer for finally receiving the ashes, and only a single drum and no intermediate platform.

In the accompanying drawing showing, by way of example, two of many possible embodiments of the invention,

Fig. 1 is a fragmental front elevation of the device;

Fig. 2 is a side or end elevation showing the upper end of the device with outer drum in closed position, part of the chute being shown in section;

Fig. 3 is a fragmental end elevation showing the drum housing with drums removed;

Figs. 4 and 5 are transverse vertical sectional views partly in elevation, respectively showing closed and open positions of the drums;

Figs. 6 and 7 are vertical sectional views of the outer and inner drums respectively;

Fig. 8 is a perspective view of the control member; and

Figs. 9 and 10 are fragmental transverse vertical sectional views respectively, showing open and closed drum positions of another form of the invention.

The improved receiver, for receiving cigar and cigarette ashes, butts and like material, as shown in Figs. 1 to 8, comprises a housing 10 including an intra-marginally open set-off plate 11 adapted to be secured around, and form a frame for, an opening in an inner wall of a closed automobile or the like, said plate being cut and turned back at the upper and lower edges to form the ash and cigarette-receiving opening 12 and to form downwardly and backwardly turned upper and lower lips 14, 15 (Fig. 2) and housing end walls 16 perpendicular to the plate. A connecting plate

18 joins the rear and lower edges of the end walls 16 to form a housing rear wall, and a bottom wall 19 cut and bent down to form downwardly pointing lower rear and end lips 20, 21.

A laterally closed upright chute 25, which may extend downwardly between the outer and inner walls of the automobile to the exterior of the automobile, receives and is secured to said lower lips 15, 20, 21.

Each end wall 16 is provided with a central perforation 26 (Fig. 3) receiving a pivot or bearing pin 27 (Figs. 1 and 5) secured therein and supporting a normally yieldable raised segmental outer drum or closure 28 normally closing said opening and bent at the upper and lower edges to form a projecting lower lip 29 (Fig. 6) and a manipulating lip 30, and provided with end walls 31 centrally pivotally received on the bearing pins 27, and provided with a radial cam slot 32 and a large opening 33 near and at the front and rear respectively of the pin 27. The lips 29 and 30 respectively engage the lips 15 and 14 to limit the movement of the drum.

A normally yieldably raised inner drum 35 or retaining means coaxially closely received in the outer drum has end walls 36 pivoted on said pin 27 and provided with a radial cam slot 36' and large opening 37 to the front and rear of the pin 27 respectively and at all times respectively registering with the large opening 33 and slot 32 of the outer drum.

A control member 39, 40 (Fig. 8) comprises an upwardly extending rod 39 slidably guided in a perforated ear 41 (Fig. 3), and a lower disk 40 having a longitudinal slot 42 received on said bearing pin 27 and a pair of control pins 43 received in said cam slots 33, 36', and upright slots 44 in the housing end walls.

A spring 45 (Fig. 2) compressed between said ear 41 and disk yieldably press the control pins 43 downwardly thereby to yieldably raise the drum portions 28 and 35, said spring permitting downward pressure on the manipulating lip 30 to lower the outer drum and therefore the inner drum, thereby to open the front of the housing and dispose the drums 28, 33 (Fig. 5) in lowered position to provide an ash-receiving tray as in Fig. 5.

Upward movement of the drums under the action of the springs 45 separates the drums at the bottom, as in Figs. 2 and 4, to permit ashes, cigarette butts and like material to drop below upon a normally horizontal platform or retaining means 48 (Figs. 2 and 5) hinged to the front inner face of the chute 25.

A pin 49 extending from an end edge of the platform and out through a slot (not shown) in the side of the chute, and a similar pin 50 extending from the end wall of the outer drum, through said arcuate slot 51, together carry and are connected by a wire link 54, whereby when the drums are raised to close the receiver, the platform is also raised to horizontal position to receive and retain material from the drums, to permit the same to burn out or become extinguished, and whereby when the drums are again lowered, as in Fig. 5, to receive subsequent material, the platform is lowered and ash or unconsumed material thereon is dropped into a receptacle 56 on the lower end of the chute.

Said receptacle comprises an upwardly open elongated passage chamber secured to and under the chute and communicating with the chute and provided with a dished floor 57 to receive material from the chute, and with flared front and rear open ends 58 for creating a draft through

the chamber when the vehicle is in motion, whereby the material or ashes are blown away when the vehicle moves.

The operation will be easily understood from the foregoing. The chute 25 and housing 10 are built into the double wall of an automobile or otherwise secured therein with the frame 11 and drum 28 exposed and the receptacle 56 longitudinally disposed beneath the vehicle.

The drum 28 is held normally closed by the spring 45. When it is desired to deposit ashes or other material, the lip 30 is pressed down until the drums move down to the position of Fig. 5, or lower, whereupon the ash is deposited within the drums.

In this position of Fig. 5, the two drums completely close the chute and prevent any up-draft that might scatter the ashes. The lip is then released and the spring 45 brings the drums back to the position of Fig. 2. But the lower edges of the drums do not separate from each other until after their upper edges have closed the front opening 12.

Before the lower edges separate and drop the material, the wire has raised the platform 48 to approximate horizontal position to catch the material, to hold the same to permit any fire to go out or burn out before being dropped, thus to avoid fire in a garage or along the road side.

The next time the receiver is used, the above operation is repeated, except that the lowering of the platform 48 spills the previously trapped material to the floor 57, where it will remain until the vehicle moves fast enough to cause sufficient draft to blow the material out at an open end 58.

The form of receiver of Figs. 9 and 10 comprises a housing 10' having front and bottom openings and end walls and lower lips 15 and 20 for connection with an upright chute as in Figs. 1 and 2. However this form is provided with a single normally yieldably raised segmental closure drum 68 normally closing said front opening and provided with an upper manipulating lip 30, a lower lip 29 and end walls 69 approximately centrally pivotally mounted on the housing end walls. A spring 70 operatively connected to said housing and drum serves for yieldably raising the drum and closing said opening.

The lower part of said drum is cut away as at 72 to form a discharge opening, to rear edge of which is hinged a normally open door 73 engageable by a projection 75 on said housing when the drum segment is lowered, whereby when the drum is lowered, the door is raised and closed, as in Fig. 9.

When the drum is raised, as in Fig. 10 a projection 76 carried at the hinged edge of the door is engaged by the upper face of said projection 75, thereby forcing the door open to spill material therefrom through the chute 25 into a box 77 on the lower end of the chute having therein a drawer 78 to receive the material dropped from the chute.

Obviously the box 77 or chamber 56 may be used with a chute used with either housing 10 or 10'; or the chute may be much shortened or, in some instances, omitted entirely. In some instances any or all of the closures and retaining means might be omitted.

The box 77 and drawer 78 are suitable for indoor use, but may be used with vehicles if desired.

The operation of the device of Figs. 9 and 10 is similar to that of the device of Figs. 1 to 9. The closure 68 is normally in the position of Fig. 10,

and when material is to be deposited, the lip 30 is depressed to the position of Fig. 9, and the material deposited in the drum, the closed door preventing exit of odors if the box 71 is used or drafts if the chamber 56 is used.

Then the lip is released, allowing the parts to assume the position of Fig. 10, dropping the material through the chute to the receptacle.

We claim as our invention:

1. A receiver for ash and cigar and cigarette butts, said receiver comprising a housing in a closed automobile and having front and bottom openings and end walls; an upright chute extending downwardly to the exterior of the automobile and communicating with said bottom opening; a normally yieldably raised segmental outer closure drum normally closing said front opening and provided with end walls pivotally coaxially mounted on the housing end walls; a normally raised inner segmental drum coaxially received in the outer drum and pivoted coaxially on said end wall; a yieldably pressed control member operatively connected to said drums for yieldably raising the drums and constraining the drums to move together; a normally horizontal platform hinged in the chute; and a link connecting said platform and outer drum and so connected that when the drums are raised the platform is also raised to horizontal position, when the drums are lowered the platform is lowered.

2. A receiver for receiving cigar and cigarette ashes, butts and like material, said receiver comprising a housing including an intra-marginally open set-off plate adapted to be secured around, and form a frame for an opening in an inner wall of a closed automobile; said plate being intramarginally cut to form the intramarginal opening and turned back at the upper edge of the opening to form a downwardly and backwardly

turned upper lip, and at the ends of the opening to form housing end walls perpendicular to the plate; a connecting plate joining the rear and lower edges of the end walls and forming a housing rear wall, and a lower wall cut and bent down to form downwardly pointing lower rear and end lips; a laterally closed upright chute extending downwardly between the outer and inner walls of the automobile to the exterior of the automobile and having its upper end receiving and secured to said lower lips.

3. A receiver comprising a housing having front and lower openings and end walls; an upright chute extending downwardly from, and joining, said lower opening; a closure means a distance below the lower opening and completely closing the chute; a normally yieldably raised segmental closure drum having a curved wall normally closing said front opening and provided with an upper manipulating lip and end walls approximately centrally pivotally mounted on the end walls of the housing; spring means operatively connected to said housing and drum for yieldably raising the drum wall and closing said front opening; the lower part of said drum wall leaving the lower opening open when the front opening is closed by the drum wall; an additional normally open door adapted to close said lower opening; and an operative connection between the door and drum such that when the drum wall is lowered said lower opening is closed and when the drum wall is raised the lower opening is opened; said drum and closure means normally cooperating to provide a closed chamber for receiving and holding material discharged from the door when the upper opening means is closed.
